UNITED STATES PATENT OFFICE.

HENRY A. CHRISTY, OF KENILWORTH, ILLINOIS.

CAR-ROOF.

1,005,938.

Specification of Letters Patent. Patented Oct. 17, 1911.

Application filed June 2, 1911. Serial No. 630,935.

To all whom it may concern:

Be it known that I, HENRY A. CHRISTY, a citizen of the United States, residing at Kenilworth, in the county of Cook and State of Illinois, have invented certain new and useful Improvements in Car-Roofs, of which the following is a specification.

The leading purpose and object of this invention is the construction of a car roof composed of sheet-metal plates in such a manner that the distortion or twisting of the car-body, due to the strains it receives in transit or due to the uneven loading of the car, will not injure nor tear the roof-covering—in other words, the main purpose of the invention is the provision of a car-roof structure which can satisfactorily withstand all usages or service without danger of causing leakage, the structure of the roof being such that it will at all times be rain-weather- and wind-proof. To reach this result I do not rigidly and fixedly attach the roof-plates to the car-roof frame, but associate the parts together in such a manner that the completed roof is what may be termed "flexible" or "yielding"—that is, the parts of the roof structure can give sufficiently or yield to the various strains without danger of rupture. A roof embodying the structural features and characteristics of this invention is very easily repaired, due to the facility with which the roof-plates may be removed and replaced, which, of course, renders the assembling of the parts in the first instance economical and free from difficulty or the employment of any great amount of labor.

In the accompanying drawings I have illustrated a preferred and desirable embodiment of the invention in order that those skilled in this art may have a full and complete comprehension of what the invention covers. In the various views of these drawings like reference characters refer to the same part throughout.

In the drawings—Figure 1 is a fragmentary perspective view of a portion of a car-roof structure incorporating my invention; Fig. 2 is a cross-section through the roof of the car; Fig. 3 is a longitudinal section on the line 3—3 of Fig. 2; Fig. 4 is a fragmentary side elevation of the car-roof structure, certain of the parts being broken away; Fig. 5 is a longitudinal section on the line 5—5 of Fig. 2; Fig. 6 is a perspective view of one of the carlines; Fig. 7 is a perspective

view of the straps which attach the edges of the roof-plates to the sides of the car-body; Fig. 8 is a perspective view of one of the roof-plates; Fig. 9 is a similar view of one of the cap-strips, and Fig. 10 illustrates, in perspective, one of the supports used at the top of the roof for the attachment of the longitudinal cap-strip, and the support of the running-boards.

By reference to the drawings, it will be observed that each carline 20 is of channel shape, in cross-section, consisting of a web 21 having along its opposite longitudinal edges a pair of upstanding stiffening flanges 22, 22, the whole carline being bent at the center to provide the proper inclination or slope to the two sides of the roof. At each end each carline has its flanges 22 cut away or omitted, the web being bent down at these points to provide attachment-plates or ears 23, 23. As is clearly indicated, these carlines are applied to the tops of the car-body side walls 24, with the ears or attachment sections 23 disposed outside of and against the outer face of the side walls. As I have indicated in the various figures, one of these carlines is used at each end of the car just inside of the end wall 25, so that one of the upwardly-extended flanges 22 rests against the inner face of such end wall. At its apex each of these carlines has resting upon it and secured to the top face of its web 20 a support 26 composed of two channel sections 27 and 28, whose webs 29 and 30 are riveted together in contact, as shown in Fig. 10, the lower flanges 31 and 32 of the support being inclined to conform to the inclination of the two sides of the carline proper, while the upper oppositely-extended flanges of the same two channel sections are disposed in a single horizontal plane. Fastened to these supports 26 I employ a cap-strip 33 of inverted channel construction—that is, its web rests directly upon and is secured to the top flanges of the various supports 26, while its marginal flanges extend downwardly, as is clearly indicated in Fig. 1. On top of the cap-strip I use cross-supports 34, to the tops of which are secured, in any approved manner, the longitudinal running-boards 35, which, as arranged side by side, are of considerably greater width than the cap-strip beneath them. If preferred, these running-boards may be made in comparatively short sections to facilitate the removal and applica-

tion of the metal roof-plates, hereinafter described. Each of these sheet-metal roof-plates consists of a main body 36 (Fig. 8) having along its upper edge a marginal upwardly-extended flange 37, the plate having also at its lower edge a downward-turned flange 38, the extreme edge of which is bent up at 39 to provide a marginal portion of double thickness. Along each of its two sides the plate 36 has a downward-turned flange 40, the lower end of which is bent inwardly at 41 in contact with and riveted to the flange 38. These various roof-plates are applied to the roof, while the outer running-boards 35 are removed, permitting the inclination of the roof-plates sufficiently to enable the operator to introduce the flange 37 beneath the corresponding side flange of the longitudinal cap-plates 33, the roof-plate being then swung downwardly into operative relation with the carlines, with its flanges 40 residing in the troughs of the carlines and disposed slightly away from the up-turned flanges of such carlines, this construction permitting movement of the car-frame and roof-plates relatively to one another without tearing or rupturing such plates. Above each half of the carline is employed a board or similar member 42, which rests upon the adjacent portions of two of the roof-plates. Each of these boards is accommodated within one of the carline-caps 43, each of the latter at its lower end having a depending ear 44, adapted to overlie the adjacent parts of the flanges 38 of two adjacent plates, and also to overlie the ear 23 of the carline in connection with which the cap-strip is used. The upper end of the cap 43 and the board 42 which it houses are received beneath the flange of the longitudinal cap-strip 33, the latter being notched at 45 for this purpose.

Extended along the top portion of each side wall of the car is a sectional strap composed of a plurality of parts 46, each of which has one end 47 offset to receive the unbent end of the next adjacent strap section. These bars are apertured at 48 in alignment with the holes 49 and 50 of the carline and cap-strip ears, and through these registering holes I employ bolts 51, which extend through the side wall of the car and hold together the various parts of the roof construction. The straps 46, as will be noticed, are positioned just above the seam or reinforced portion 39 of the various flanges 38 of the car-roof plates.

At each end of the car-body I use a very narrow plate 52, which in other respects is substantially like the broader and more substantial plates forming the roof covering. The outer marginal flange 53 of the plate 52 is disposed just outside of and bears against the outer face of the end wall 25, all as is clearly shown in Figs. 1, 3 and 5.

It should be apparent from this description and illustration that each of the roof-plates has a loose connection with the various carlines, and is loosely received beneath the cap-strip 33, so that as the car-body yields or deflects or becomes distorted, or the side walls bulge outwardly, these plates can give or yield relatively to the roof-frame without their becoming torn or otherwise injured. Furthermore, any plate may be readily removed and replaced by merely removing one or more of the straps 46, unscrewing the nuts from two of the bolts 51, taking off two of the cap-strips and boards 42, and then turning upwardly and drawing outwardly the roof-plate in such a manner as to free the flange 37 from the flange of the cap-strip 33, it being assumed that one of the running-boards or a section of the same has been taken off to permit such removal of the roof-plate. Just as easily a new or repaired roof-plate can be put back into place. It should be clear that the roof-plates, carlines and cap-strips are secured rigidly only to the side walls of the car, and that the car-body does not possess what might be termed the usual "ridge-pole," although such a longitudinal strengthening member may be employed if found to be desirable or necessary. In reality the longitudinal centrally disposed cap-strip 33 acts somewhat as a ridge-pole and operates to maintain the carlines properly spaced apart.

Preferably the wooden or other fillers 42 are of sufficient height to prevent the longitudinal depending flanges of the cap-strips from contacting with the top surfaces of the roof-plates. Owing to this construction, there is no wear or cutting of the cap-strips on the roof-plates. In other words, there is no wearing of metal on metal. Furthermore, the supports 26 at the tops of the carlines assist in preventing the carlines from straightening out—that is, assist in preventing the roof from being displaced or distorted.

To those skilled in the art various structural changes will occur with respect to the construction herein set forth in detail which will fall within the scope and breadth of the appended claims because my invention is not limited and restricted to the precise and exact structural features herein illustrated and described, but many minor mechanical changes may be made therein without departing from the essence of the invention and without sacrificing any substantial benefits.

What I claim is:

1. In a car-body construction, the combination of car-body side walls, a roof-frame having channel carlines with upstanding flanges, and roof-plates having marginal depending flanges accommodated in the troughs of and resting upon the webs of said

channel carlines, the flanges of the latter being out of contact with the under surfaces of the roof-plates, said roof-plate flanges constituting the sole support of the roof-plates on the carlines, substantially as described.

2. In a car-body construction, the combination of car-body side walls, a car roof-frame having channel carlines secured to the side walls of the car-body, said carlines having upstanding flanges, roof-plates having depending flanges accommodated in the troughs of said channel carlines and resting on the webs of such carlines to hold the roof-plates above the flanges of said carlines, and cap strips over said carlines, said roof-plate flanges constituting the sole support of the roof-plates on the carlines, substantially as described.

20 3. In a car-body construction, the combination of car-body side walls, a car-roof having channel carlines with upstanding marginal flanges, and roof-plates having depending flanges accommodated in the troughs of said channel carlines, the flanges of the carlines and roof-plates being spaced apart from one another to give flexibility to the roof structure, said roof-plate flanges resting upon the webs of the channel carlines and being of such width as to maintain the roof-plates out of contact with the edges

of the carline flanges, substantially as described.

4. In a car-body construction, the combination of car-body side walls, cambered channel carlines extending from side wall to side wall and having at their opposite ends depending ears fixedly secured to said side walls, said carlines having upstanding longitudinal marginal flanges, a support fastened to each of said carlines at its apex, a longitudinal centrally disposed cap-strip secured to said supports and having depending longitudinal marginal flanges, metal roof-plates having depending flanges accommodated in the troughs of said channel carlines, the lower edges of said roof-plate flanges resting upon the webs of said carlines to support the roof-plates above the top edges of the carline flanges, each of said roof-plates having along its inner edge an upwardly extending flange disposed beneath said longitudinal cap-strip and spaced inwardly away from the depending flange of the latter, and carline caps located above 55 said carlines and fixedly secured only to the car-body side walls, substantially as described.

HENRY A. CHRISTY.
